UNITED STATES PATENT OFFICE.

EDWARD R. GREEN, OF KANSAS CITY, MISSOURI.

CROSSING SIGNAL.

Application filed March 22, 1928. Serial No. 263,681.

This invention relates to traffic signals of that general class which visually indicate the direction of permitted and forbidden flow of traffic at street intersections under the control of traffic officers and more especially to word signals of the "Go" and "Stop" variety. With such signals it is the custom of the officers upon leaving their stations for short periods, to turn the signals to an intermediate position so that uncontrolled traffic through the intersection may occur in both directions, the drivers and pedestrians passing under such conditions at their own risk and at the risk of collisions or accidents resulting from the passage of privileged traffic, such as police patrol cars, ambulances and fire apparatus.

Accordingly one of my objects is to provide a caution signal to clearly inform traffic on both streets that travel through the intersection is free in both directions and hence caution must be observed, as distinguished from the turned signal mentioned, which are not always understood by strangers or tourists who sometimes come to a full stop upon observing the turned signal and are crashed into by following traffic familiar with the system and therefore not expecting a stop on the part of traffic ahead.

Another object is to provide means whereby the adjustment of the "Go" signals when traffic is to be arrested, shall operate an audible signal to attract attention to the exposed "Stop" signals.

Another object is to provide an audible signal for operation by the officer in control to warn all traffic of the impending passage of privileged traffic, such as police patrols and the like.

A still further object is to provide a signal of simple, strong, durable and inexpensive construction.

With these general objects in view the invention consists in certain novel and useful features of construction and combinations of parts as hereinafter described and claimed; and in order that it may be fully understood, reference is to be had to the accompanying drawings, in which:

Figure 1 is a perspective view of a traffic crossing signal embodying the invention, but lacking corner lamp reflectors disclosed by Figures 2, 3 and 8.

Figure 2 is a top plan view of the signal.

Figure 3 is a view taken generally through

the center of the upper part of the signal and showing certain features in the foreground in elevation.

Figure 4 is a detailed perspective view of the caution signal element. 60

Figure 5 is a fragmentary perspective view of a part of the signal.

Figure 6 is an enlarged detail perspective view illustrating more clearly the construction of the gong-operating latches and the 65 relation of said latches to the gong-operating lever.

Figure 7 is an enlarged detail illustrating the pivotal connection of the handle to one of the signal operating rods. 70

Figure 8 is a detail perspective view of one of the corner lamp-holding reflectors to illuminate the "Stop" and "Go" signals for night-time use.

Referring now to the drawings in detail, 75 1 indicates a heavy base, 2 a tubular standard extending upward from the base a distance approximately seven feet, and 3 a rectangular casing surmounting the standard, each side of the casing being provided at its 80 lower end with an opening 4.

The casing is provided with inner walls 5 spaced from the outer walls and extending from the bottom to a plane slightly above the upper edge of the openings 4, and 85 the bottom is stiffened and strengthened by a spider frame 6, the central portion of which depends through the bottom and is engaged by the upper end of the standard 2. The outer faces of the four sides of the 90 inner wall bear the words "Stop" visible and readable through the openings 4 when said openings are uncovered by a series of four slides 7 interposed between the inner and outer walls and susceptible of being disposed in raised or inoperative position or in lowered or operative position, as hereinafter appears. The outer faces of the slides bear the words "Go" so that said words may be readily seen by approaching 100 traffic when the slides are in their operative or depressed positions, that is, when resting on the bottom of the casing, as indicated by full lines in Figure 3. Opposite slides are 105 rigidly connected together by crossed frames spaced apart vertically a distance somewhat in excess of the height of the openings 4. The said frames are preferably connected to their respective slides in a horizontal plane above the inner walls, and the bridge por-

tion 8 of one of said frames, is preferably arched upward and the bridge portion 9 of the other is in the form of an inverted arch. The arched or bridge portions of said frames are formed with rigid horizontal loop portions 10, to accommodate features of construction hereinafter identified. By vertically spacing the arched portions as explained, it will be apparent that either set 10 of the slides may be raised high enough to fully uncover the respective openings 4 without interfering with the other arched portion. This is necessary because the slides, as stated, all bear the word "Go", and in practice it is never desirable to elevate all four slides at the same time except when ordinary traffic is forbidden and privileged traffic has the right of way in all directions. For ordinary traffic control when 20 the "east" and "west" slides are exposed, the "north" and "south" slides should be raised so as to expose the "north" and "south" words "Stop", the reverse being true when it is desired to permit "north" and "south" 25 traffic to flow and forbid the flow of "east" and "west" traffic.

Fitting in the inner corners of the casing above the slides are angle spacers 11, and secured in the angles of said spacers are 30 angle guides 12, the guides being of the same length but greater width than the spacers so that in conjunction with the outer walls of the casing, the guide grooves 13 are provided which in effect are continuations 35 of the spaces between the walls.

For the operation of the two sets of slides there are provided vertical lift rods 14 and 15 respectively, the rod 14 being rigidly secured in any suitable manner to the arch 8 40 and the rod 15 to the inverted arch 9. Said rods extend down through the tubular standard a few feet, or far enough for the respective horizontal handles 16 and 17 to be conveniently accessible to a traffic officer in 45 charge of the signal. The handles are suitably attached to the lower ends of the rods to lift the same, but are capable of a slight pivotal movement on the rods. They project at right angles to each other through 50 vertical slots 18 and 19 in the tubular standard, and at the upper ends of said slots are offset slots 20 and 21, wherein the handles may be set when it is desired to support the 55 slides in elevation position, the slots being of the bayonet variety as the simplest provision for permitting operation of the handles and for securing them in elevated position.

Arranged within the casing is a series of 60 four plate signals 22 facing properly for the guidance of traffic. These four signals bear upon their outer faces the word "Caution," and are connected together so as to operate as a single unit by a horizontal frame 23, 65 the said frame at opposite sides, having de-

pending U-portions or legs 23^a which rest upon the bottom of the casing when the caution signals are in inoperative position wholly within the casing. Two of the caution signal plates are connected by a bridge 70 or cross bar 24, and extending downward from said cross bar into the tubular standard is a rod 25 provided at its lower end with a horizontal handle 26 of the type hereinbefore described, for operation in a bayonet slot 27 in the tubular standard. The handle 27 is preferably disposed a considerable distance below the handles of the "Go" slides, as the caution signal will be used only occasionally and hence it is preferred to 80 dispose the handle at such a point that the officer could not readily operate it by mistake and thus perhaps confuse traffic at an inopportune moment. The caution signal is exposed by raising the plates to the position 85 indicated by dotted lines, Figure 3, and when in such position advises that traffic may flow in both directions but that due caution should be observed.

As it is desirable to call attention of traffic 90 by sound as well as by sight, an alarm mechanism is provided. As shown 28 indicates a gong of the type conventional on fire apparatus. It is mounted on a plate 29 supported by a standard 30 secured to the spider 95 frame 6, or in any other suitable manner. A clapper 31 is pivoted to plate 29 to strike the gong, and to effect the operation of the clapper each time a set of the "Go" signals are raised, a lever 32 is pivoted at 33 to the plate 29. This lever at one side of its pivot carries a pivoted bell-crank 34 connected by a retractile spring 35 to the plate 29, one end of the bell-crank being adapted as the lever is rocked, to engage a lug 36 on the 100 clapper and depress the latter against the resistance of a retractile spring 37 connecting the clapper to plate 29. As the bell-crank passes clear of the lug of the clapper, the latter is swung upward forcibly by the 105 tensioned spring 37 and caused to strike the gong. The lever 32 when released is returned to its initial position by the spring 35 because the bell-crank will pivotally operate to accommodate such return. The 110 mechanism of the alarm has been referred to in some detail but it is not new per se and it is therefore thought that the preceding reference is sufficient to make its operation 115 perfectly clear.

To effect the operation of lever 32, arch 8 is provided with an upstanding post 38 equipped with a bevelled pivoted spring latch 39, so that when the said arch is moved upward to raise its connected slides, the latch engages and swings the lever upward. During this movement the clapped is forced downward by the bell-crank until the latter rides off the lug and releases the clapper and eventually the latch slides from under 120 125 130

the lever and permits the latter to be returned to normal position. When the said slides are lowered, the spring of the latch 39 yields so that the latter can pass the lever. 5 To operate the gong in the same way when the other pair of slides is raised, the inverted arch 9 is equipped with an upwardly projecting standard 40 provided with a similar spring latch 41, the arrangement being 10 such that upward movement of arch 9 causes its latch to operate the lever and effect the operation of the clapper, the latch yielding when the frame is again moved downward. It will thus be seen that each time a pair 15 of the "Go" signals are raised, the audible signal operates to attract the attention of traffic to the visual signal.

It is desirable also that when privileged traffic is about to pass, the ordinary traffic 20 shall be notified to clear the street. To accomplish this result it is desirable to raise both sets of slides so that the "Stop" signal only shall be exposed and for the traffic officer to operate the gong in a practically continuous manner. To do this a cable 42 runs 25 part way through the tubular standard and is attached at its upper end to the lever 32 at the opposite side of the pivot thereof from the end for engagement by the spring latches 30 39 and 41 mentioned. The cable runs over a suitable guide pulley 43, and at its lower end through an opening 44 in the standard, and is provided at its lower extremity with an accessible handle 45 so that the officer can 35 impart quick successive jerks or pulls on the cable to effect the rapid operation of the gong and thus warn traffic of the impending passage of a police patrol vehicle, an ambulance or fire apparatus.

40 When night has fallen the crossing signal is of practically no value unless illuminated so that the words "Stop", "Go" and "Caution" may be readily seen at a sufficient distance for traffic to slow down, or stop if necessary, as the intersection is reached. As 45 a convenient means of providing illumination for the signal herein described, I have provided four corner reflectors to contain electric or other lamps, not shown, each signal 50 comprising a bottom portion 46 fastened in any suitable manner to the bottom of the casing, a right angle shaped wall 47 rising from said bottom portion 48 to about the height of the openings 4 and inwardly projecting top flanges 48 extending from the 55 top of walls 47 to and against the adjacent walls of the casing, thus providing for the reflection of light from each lamp along two sides of the casing so as to illuminate the 60 signals at the time exposed, through the openings 4.

From the above description, it will be apparent that I have produced a crossing signal embodying the features of advantage 65 set forth as desirable in the statement of

the objects of the invention, and while I have illustrated and described the preferred embodiment of the invention, it is to be understood that I reserve the right to make all changes properly falling within the principle of construction and mode of operation involved and within the spirit and scope of the appended claims. 70

I claim:

1. A signal comprising a casing having 75 angularly-disposed walls provided with openings, fixed inner walls for and spaced from the outer walls of the casing, and bearing direction signal words on their outer sides visible through the respective openings, slides between the inner and outer walls of the casing and bearing signal words on their outer sides, of opposite import to the signal words of the inner walls, and means to simultaneously adjust pairs of 80 opposite slides in the same direction, to span the respective openings and expose their respective signal words therethrough, and hide the exposed portions of the respective inner walls from view, or to a position back of the respective casing walls to uncover the openings thereof and expose the signal words of the corresponding sides of the inner walls. 85

2. A signal comprising a casing having 90 angularly-disposed openings in the sides, an inner wall for and spaced from the outer wall of the casing, and bearing direction signal words visible through said openings, slides between the inner and outer walls of 95 the casing and bearing signal words of opposite import to the signal words of the inner wall, means to simultaneously adjust opposite slides to span the said openings and hide the exposed portions of the inner wall 100 from view or to assume a position out of view from the traffic, to expose the signal words of the corresponding sides of the inner wall, and an audible signal automatically operated each time a pair of 105 opposite slides are operated to disclose a pair of the signal words of opposite import from those of the slides. 110

3. A signal comprising a casing having 115 angularly-disposed openings in the sides, an inner wall for and spaced from the outer wall of the casing, and bearing direction signal words visible through said openings, slides between the inner and outer walls of the casing and bearing signal words of opposite import to the signal words of the inner wall, means to simultaneously adjust opposite slides to span the said openings and hide the exposed portions of the inner wall 120 from view or to assume a position out of view from the traffic to expose the signal words of the corresponding sides of the inner wall, a caution signal comprising four sides connected as a unit, fitting within and hidden by the casing and normally resting 125 130

thereon, and means for elevating said signal to a plane above the top of the casing to expose the signal to traffic in all directions.

4. A signal comprising a casing having angularly-disposed openings in the sides, an inner wall for and spaced from the outer wall of the casing, and bearing direction signal words visible through said openings, slides between the inner and outer walls of the casing and bearing signal words of opposite import to the signal words of the inner wall, means to simultaneously adjust opposite slides to span the said openings and hide the exposed portions of the inner wall from view or to assume a position out of view from the traffic to expose the signal words of the corresponding sides of the inner wall, an audible signal mechanism within the casing, and means actuated by upward movement of either set of slides for operating such signal mechanism.

5. A signal comprising a casing having angularly-disposed openings in the sides, an inner wall for and spaced from the outer wall of the casing, and bearing direction signal words visible through said openings, slides between the inner and outer walls and bearing signal words of opposite import to the signal words of the inner wall, crossed arch frames inverted with respect to each

other and connecting opposite slides in pairs, a rod connected to each of the said frames for raising and lowering the respective pairs of slides, and an audible signal mechanism actuated by upward movement of either of said rods.

6. A signal comprising a casing having angularly-disposed openings in the sides, an inner wall for and spaced from the outer wall of the casing, and bearing direction signal words visible through said openings, slides between the inner and outer walls and bearing signal words of opposite import to the signal words of the inner wall, crossed arch frames inverted with respect to each other and connecting opposite slides in pairs, a rod connected to each of the said frames for raising and lowering the respective pairs of slides; a gong within the casing, a spring-actuated clapper therefor, mechanism for setting and releasing the clapper to strike the gong, and spring latches movable with said rods for respectively operating said mechanism when the slides are moving upward and to be tripped by and without affecting said mechanism when the slides are lowered.

In testimony whereof I affix my signature.

EDWARD R. GREEN.
